GUIDE MEMBER FOR ROCK DRILLS

William A. Smith, Sr., Athens, Pa., assignor to
Ingersoll-Rand Company, Jersey City, N. J., a
corporation of New Jersey

Application March 1, 1935, Serial No. 8,809

6 Claims. (Cl. 255—45)

This invention relates to rock drills, and more particularly to a guide member for rock drills of the type which are mounted slidably in supporting shells whereby they are held in correct relationship with respect to the work.

One object of the invention is to minimize the expense of maintenance of rock drills of this type by providing the rock drill with detachable guide ribs which may be replaced when worn to a state 10 of unserviceability without necessitating the additional and comparatively greater expense of replacing a casing part.

Another object is to equip the rock drill with a guide member that will remain secured rigidly 15 in the assembled position on the rock drill.

Other objects will be in part obvious and in part pointed out hereinafter.

In the drawing accompanying this specification and in which similar reference numerals refer to similar parts,

Figure 1 is a longitudinal side elevation of a rock drill equipped with a guide member constructed in accordance with the practice of the invention,

Figures 2, 3 and 4 are transverse views taken through Figure 1 on the lines 2—2, 3—3 and 4—4, respectively, and

Figure 5 is a transverse view taken through Figure 3 on the line 5—5.

Referring more particularly to the drawing, 20 designates the guide member and 21 a rock drill to which the guide member is applied.

The rock drill 21, of which only certain of the casing parts are shown for the sake of simplicity 35 of illustration, comprises a cylinder 22 and front and back heads 23 and 24, respectively, which may be secured to the cylinder by the usual side rods 25, only one of which is shown.

In accordance with the practice of the invention 40 the cylinder 22 is provided with a base portion or rib 26 which extends longitudinally of the cylinder and preferably terminates at or near the ends thereof. The bottom of the base 26 is in the form of a flat surface 27 which seats upon a similar surface 28 of the guide member 20, and in the surfaces 27 and 28, which are of the same width, are transverse registering slots 29 and 30 containing a key 31 which serves to hold the cylinder and the guide member against relative longitudinal movement.

In the transverse view the base 26 has the appearance of a dove-tail of which the side surfaces 32 incline generally in the direction of the axis of the cylinder. The adjacent portion 33 of the 55 plate 22 is likewise of dove-tail shape although

inverted. Its side surfaces 34, therefore, decline toward the axis of the plate and preferably have the same degree of inclination as the surfaces 32.

The surfaces 32 and 34 preferably extend along the entire length of the base 26 and the plate 20 5 and serve as seating surfaces for clamping plates 35 arranged on opposite sides of the base 26. The clamping plates are provided with V-shaped grooves 36 to receive the portions of the base and the plate defined by the inclined surfaces. 10

In order to secure the clamping plates 35 fixedly in the assembled positions said plates and the base 26 and the portion 33 of the plate 20 are provided with registering holes 37 for the reception of securing means illustrated as being in the 15 form of rivets 38. Any suitable number of rivets may be employed for this purpose and as a preferred form of construction the outer ends of the portions of the holes 37 in the plates 35 are countersunk to permit of the ends 39 of the rivets 20 being peined thereinto. The holes 37 are preferably so located that their longitudinal axes substantially coincide with the plane of the surfaces 27 and 28. Thus, semi-circular slots 40 will be located in both the base 26 and the portion 33 25 and these slots register with each other to accommodate the intermediate body portions of the rivets 38. As will be readily understood, therefore, the rivets will be embedded equally in both the base 26 and the portion 33 of the plate 20 30 to augment the locking effect of the key 31.

In the arrangement shown the key 31 is arranged in the transverse plane of a rivet 38 which extends through the key. Thus, the clamping plates 35 will overlie the ends of the key slots 29 35 and 30 to retain the key 31 therein.

The plate 20 is provided on its opposite sides with guide ribs 41 adapted to extend slidably into the guideways of a rock drill shell (not shown) and which may be of a well known type commonly 40 employed for guiding and maintaining the rock drill in the correct relationship with respect to the rock being drilled. The plate 20 is, moreover, provided at its rear end with a lug 42 to receive a feed nut 43 which is suitably threaded internally 45 for cooperation with a feed screw (not shown) but thereby the force is applied to the rock drill for actuating it longitudinally of its supporting shell.

In practice, the present invention has been 50 found to be highly efficient and to effect a considerable economy in the matter of maintenance of the drilling apparatus. It is a well known fact that the guide portion, such as the ribs 41 of the present structure, are exposed to severe 55

usage and to consequent great wear. This is a factor which, in structures wherein the guide ribs form an integral portion of the drill cylinder, is a cause of great expense since when the guide ribs become worn to a state of unserviceability it is necessary to discard the entire cylinder. Constructed as in the present invention, whenever the guide ribs become worn only the comparatively inexpensive plate 26 need be replaced.

10 I claim:

1. In a guide member for rock drills, the combination of a rock drill casing and a plate having guide portions, clamp means extending longitudinally of and on opposite sides of the casing and the plate and engaging each, and means for securing the clamp means fixedly to the casing and the plate.
2. In a guide member for rock drills, the combination of a rock drill casing and a plate having guide portions, inclined surfaces on opposite sides of the casing and the plate, clamp means engaging the inclined surfaces, and means for securing the clamp means fixedly to the casing and the plate.
3. In a guide member for rock drills, the combination of a rock drill casing and a plate having guide portions, there being inclined surfaces on adjacent portions of the casing and the plate and extending longitudinally thereof, clamping plates engaging the inclined surfaces, and means

seated in the casing and the plate and engaging the clamping means for securing the clamping means fixedly to the casing and the plate.

4. In a guide member for rock drills, the combination of a rock drill casing and a plate having guide portions, there being inclined surfaces on adjacent portions of the casing and the plate, clamping plates having V-shaped grooves to receive the inclined surfaces, and rivets embedded in the adjacent surfaces of the casing and the plate and securing the clamping plates fixedly to the inclined surfaces.

5. In a guide member for rock drills, the combination of a rock drill casing and a plate seating against the casing and having guide portions, clamp means extending along opposite sides of the casing and the plate for clamping the casing and the plate together, and means inserted in the confronting surfaces of the casing and the plate to prevent relative longitudinal movement therebetween.

6. In a guide member for rock drills, the combination of a rock drill casing and a plate having guide portions, a key inserted in the confronting surfaces of the casing and the plate, clamping means for clamping the casing and the plate together and for retaining the key in the plate and the casing, and means for securing the clamping means fixedly in position.

WILLIAM A. SMITH, SR.
